MANUALLY CONTROLLABLE CODED TRACK
CIRCUIT SIGNALING SYSTEMRobert M. Gilson, Pittsburgh, Pa., assignor to
The Union Switch & Signal Company, Swiss-
vale, Pa., a corporation of Pennsylvania

Application September 30, 1947, Serial No. 776,995.

1 Claim. (Cl. 246—38)

1

My invention relates to coded track circuits for railway signaling systems of a type which may be deenergized, and particularly to improved means for insuring proper operation of such a system under varying conditions of ballast resistance and track battery voltage.

It has heretofore been proposed in such systems to provide a series approach relay at the exit end of each track section which is connected in series with the battery from which energy is supplied to the track circuit. The lighting of signals and the control of directional stick relays are governed by this relay, so that when a train is approaching a signal, the approach relay will operate to supply energy to the lamp of the signal and will also pick up the directional stick relay to clear the signal in the rear of the train after the train has passed out of the track section.

Difficulty may be encountered in such arrangements because of variation in ballast resistance and in the voltage of the track battery.

If the equipment is adjusted to operate to provide adequate approach lighting of a signal under conditions of high ballast resistance and low battery voltage, then under conditions of low ballast resistance and high battery voltage the approach relay may operate without a train occupying the track section and thus cause improper energization of the associated directional stick relay as well as improper lighting of the lamps of the associated signal.

Accordingly, an object of my invention is to provide improved means of the type described which is arranged so that under varying conditions of ballast resistance and track battery voltage, the approach relay will always operate to initiate lighting of the associated signal on the approach of a train within a predetermined distance of the signal, and so that when the section is not occupied the approach relay will not operate and will not prevent release of the associated directional stick relay.

Another object of my invention is to provide an improved arrangement of coded track circuit apparatus in which a series approach relay is employed.

A further object of my invention is to provide a coded track circuit railway signaling system of the type described in which the voltage of the energy supplied to the track circuits of the system is maintained within selected limits.

Another object of my invention is to provide improved means of the type described in which the series approach relay is prevented from oper-

ating if no train is occupying the associated track section.

A further object of my invention is to provide means responsive to the voltage of a track battery and controlling the voltage of the energy supplied from the battery to the rails of the associated track section, the voltage responsive means being governed so as to be energized from said battery only when operating conditions require energy to be supplied from the battery to the associated track section.

In practicing my invention, I provide an over-voltage relay which has a winding connected across the terminals of the track battery for a track section by a circuit including contacts of relays which operate to complete the circuit when the signaling system has been prepared for the movement of a train through that section. The over-voltage relay is constructed and adjusted so that its contact remains released for all voltages under a predetermined value, and so that its contact will pick up at all voltages over that predetermined value. A resistor is connected in series with the approach relay and the track battery in the circuit for supplying energy to the rails of the track section and this resistor is shunted by a circuit including a back contact of the over-voltage relay, so that when the over-voltage relay is released, the resistor is shunted, and when the over-voltage relay is picked up, the resistor is effectively connected in series with the track circuit.

Other objects of my invention and features of novelty will be apparent from the following description taken in connection with the accompanying drawing.

I shall describe one form of apparatus embodying my invention and shall then point out the novel features thereof in the claim.

Referring to the accompanying drawing, there is shown a stretch of railway track having track rails 1 and 2 which are divided by the insulated joints 3 to form separate track sections 5T and 7T, and over which traffic normally moves in a direction indicated by the arrow, that is, from left to right. The signals 5S and 7S, are of the well-known color light type, and each has a green lamp G, a yellow lamp Y, and a red lamp R, and govern the movement of traffic into the sections 5T and 7T, respectively.

The section 7T is assumed to be the last section of a stretch of railway equipped with a normally deenergized coded track circuit signaling system, and the equipment located at the right-hand end of section 7T includes a control

contact L, by which the system may be energized to prepare the system for a train movement through the stretch, from left to right, and by which the signaling system may be deenergized when its operation is not required. The contact L may be controlled in any appropriate manner, as for example, through a C. T. C. system by an operator at a remote control point.

Energy for the operation of the various relays other than the track relays is furnished by suitable sources of direct current, not shown, whose positive and negative terminals are designated B and C, respectively.

The track batteries employed in this system are of the primary battery type and the voltage of the energy supplied therefrom varies between relatively wide limits throughout the life of the batteries.

In the system as shown herein, code transmitters of the pendulum type designated 180CT and 15CT are energized continuously and operate their contacts periodically at a rate of 180 or 75 times per minute, respectively, to periodically operate a transmitter relay, such as relay 5CTP, by which the coded energy of the selected frequency is supplied to the section rails.

Each code following track relay, such as 7TR, governs decoding means represented by the rectangle DM, to control a code detector relay, such as relay 7H, and a clear signal control relay, such as relay 7D. The decoding means DM may be any of the types well-known in the art, and it is not shown in detail since it forms no part of my invention. However, it is to be understood that the relay 7H will become picked up when the code following track relay 7TR is operating at either the 180 code rate or the 75 code rate, and relay 7D becomes picked up when and only when the code following track relay is operating at the 180 code rate. The supply of energy to the lamps of the signal 7S is governed by contacts of the relays 7H and 7D.

A directional stick relay, such as relay 7SR, is provided at each of the intermediate signal locations to provide means for permitting following traffic movements, and is governed by a contact of the approach repeater relay 1APR, which is a slow release repeater relay controlled by the code following series approach relay 7AR, and also by the code detector relay 7H.

The over-voltage relay OVR has its winding connected across the terminals of the track battery 5TB by a circuit including front contacts of relay 7H and 7SR in multiple.

Explanation of the arrangement of apparatus comprising my invention will be made clear by the following description of the operation of the equipment.

In describing the operation of this equipment, it is assumed that the equipment is in its de-energized condition, as shown. It will now be assumed that the contact L is closed to prepare the system for movement of a train through the stretch from left to right, and that traffic conditions in advance are such that control relay CR is picked up. Accordingly, a circuit is established to supply energy of 180 code frequency to the transmitting relay 7CTP. This circuit is traced from terminal B, over front contact a of code transmitter 180CT, over front contact a of relay CR, over contact L in its closed position, and through the winding of relay 7CTP to terminal C, and causes the contact of relay 7CTP to be operated at the 180 code rate.

When contact a of relay 7CTP picks up, it 75

establishes the circuit for supplying energy from battery 7TB over the rails of section 7T to winding of track relay 7TR, and the contact a of relay 7TR picks up. When contact a of relay 7CTP releases, it interrupts the circuit traced above, and the contact of relay 7TR releases. Accordingly, at this time, the coded energy supplied to the right-hand end of the rails of section 7T causes the contact of relay 7TR to be operated at the 180 code rate. The operation of contact a of relay 7TR at the 180 code rate causes energy to be supplied through the decoding means DM to pick up the relays 7H and 7D. The circuit for supplying energy to the green lamp G of signal 7S is now prepared by front contact a of relay 7D and front contact a of relay 7H, but this circuit is interrupted by front contact a of relay 1APR, which is released at this time, so that the green lamp G of the signal remains dark.

When relay 7H picks up, its contact c connects the winding of relay OVR across the terminals of the battery 5TB so that the relay OVR measures the voltage of the battery 5TB. If the voltage of this battery exceeds a predetermined value the contact of relay OVR will pick up, and thereby cause resistance R2 to be included in the circuit for supplying energy from battery 5TB to the rails of section 5T, but if the voltage of the battery is less than this predetermined value the contact of relay OVR will remain released and shunt resistance R2 so that this resistance is in effect removed from the circuit for supplying energy from the battery 5TB to the rails of section 5T.

When relay 7H picks up, its contact b establishes the circuit for operating the contact of transmitting relay 5CTP at the 180 code rate. This circuit is traced from terminal B, over front contact a of code transmitter 180CT, over front contact b of relay 7H and through the winding of relay 5CTP to terminal C. Accordingly, at this time the contact a of relay 5CTP is picked up and released 180 times per minute.

When contact a of relay 5CTP picks up, it establishes the circuit for supplying energy to the winding of relay 5TR over the rails of section 5T. This circuit is traced from the positive terminal of battery 5TB, through resistor R2, through resistor R1 and the winding of relay 7AR in multiple, over front contact a of relay 5CTP, over rail 1 of section 5T, through the winding of relay 5TR, and over rail 2 of section 5T to the negative terminal of battery 5TB. At this time, as explained above, the circuit governed by contact a of relay OVR for shunting the resistor R2 is open or closed depending on whether or not the voltage of the battery 5TB is high enough to pick up relay OVR. As hereinabove explained this insures that the energy supplied from battery 5TB will not be too high or too low to produce proper operation of the relays 5TR and 7AR.

The supply of energy through the winding of relay 5TR causes the relay contact to pick up, while the winding of relay 7AR and resistor R1 are proportioned so that the current which flows through the winding of relay 7AR at this time is of insufficient value to pick up the contact of relay 7AR. When contact a of relay 5CTP releases, the supply of energy to the winding of relay 5TR is interrupted, and its contact releases. Accordingly, at this time, the coded energy supplied over the rails of section 5T from battery 5TB causes the contact of relay 5TR to be operated at the 180 code rate. The operation of contact a of relay 5TR at the 180 code rate causes

energy to be supplied to the decoding means DM, and as a result, the contacts of relays 5H and 5D become picked up, thereby preparing the circuit for lighting the green lamp G of signal 5S.

It is now assumed that with the system energized as described above, a train moving from left to right passes signal 5S and enters section 5T. When the train enters section 5T the supply of coded energy to the winding of relay 5TR is shunted by the wheels and axles of the train and contact *a* of relay 5TR releases and remains released, with the result that the supply of energy through the decoding means DM to relays 5H and 5D is cut off and these relays release. When contact *b* of relay 5H releases, it interrupts the circuit for the green lamp G of signal 5S and establishes the circuit for the red lamp R of the signal.

At this time, relay 5CTP continues to operate its contact, supplying coded energy from battery 5TB to the rails of section 5T through resistor R1 and the winding of relay 1AR in multiple, through resistor R2, and also over contact *a* of relay OVR if relay OVR is released. Due to the shunting effect of the wheels and axles of the train, the current supplied to the rails from battery 5TB increases as the train approaches signal 1S. The various parts of the equipment are arranged and proportioned so that when the train advances within a substantial distance of signal 1S, as for example, 4000 ft., the value of the current which flows through the winding of approach relay 1AR becomes sufficient to operate the contact of the relay. Each time contact *a* of relay 1AR picks up, energy is supplied to the slow release repeater relay 1APR. Accordingly, relay 1APR is energized, and its front contact *a* completes the circuit including front contact *a* of relay 1H and front contact *a* of relay 1D for supplying energy to the green lamp G of signal S so the signal S displays a proceed aspect to the approaching train.

Additionally, when relay 1APR picks up, its contact *b* establishes the pick-up circuit for the directional stick relay 1SR. This circuit is traced from terminal B, over front contact *b* of relay 1APR, over front contact *d* of relay 1H and through the winding of relay 1SR to terminal C. When relay 1SR picks up, its contact *c* completes an additional circuit to supply energy to relay OVR from the battery 5TB.

When the train passes signal 1S and enters section 1T, relay 1TR is shunted and its contact *a* remains released, thereby cutting off the supply of energy through the decoding means DM to the relays 1H and 1D and these relays release. When contact *a* of relay 1H releases, it interrupts the supply of energy to the green lamp G of signal S and establishes the circuit for supplying energy to red lamp R of the signal. When contact *d* of relay 1H releases, a stick circuit is established to maintain the relay 1SR energized, and is traced from terminal B, over back contact *d* of relay 1H, over front contact *a* of relay 1SR and through the winding of relay 1SR to terminal C. Also, when relay 1H releases, its contact *c* in the circuit previously traced for supplying energy to the winding of relay OVR from battery 5TB is open, but the winding of relay OVR remains connected across the battery 5TB over front contact *c* of relay 1SR so the relay OVR continues to measure the voltage of the battery 5TB.

When contact *b* of relay 1H releases, it interrupts the circuit previously traced for supplying energy coded at the 180 code rate to the transmitting relay 5CTP, and establishes a circuit for

supplying energy coded at the 75 code rate to relay 5CTP. This circuit is traced from terminal B, over front contact *a* of code transmitter 15CT, over front contact *b* of relay 1SR, over back contact *b* of relay 1H, and through the winding of relay 5CTP to terminal C.

As a result, energy is now supplied to the rails of section 5T at the 75 code rate, and since the rear portion of the train still occupies section 5T, 10 the approach relay 1AR will now operate its contacts at the 75 code rate, and relay 1APR will remain energized.

When the train under discussion vacates section 5T, the removal of the shunt decreases the 15 value of current supplied to the section rails from the battery 5TB, and as a result the energy flowing through the winding of relay 1AR falls below the value necessary to pick up the contact of relay 1AR and its contact remains released. Accordingly, energy is no longer supplied to relay 1APR over the circuit including front contact *a* of relay 1AR, and after a short time interval, the contacts of relay 1APR release.

When contact *a* of relay 1APR releases, it 20 interrupts the supply of energy to the red lamp R of signal S and it becomes extinguished. Additionally, when relay 1APR releases, its contact *b* interrupts the pick-up circuit previously traced for supplying energy to relay 1SR, but relay 1SR remains picked up by the energy supplied over its stick circuit which includes back contact *d* of relay 1H and front contact *a* of relay 1SR.

As relay 1SR remains picked up when section 25 5T is vacated, the relay 5CTP continues to be operated at the 75 code rate and supplies energy from battery 5TB over the rails of section 5T to relay 5TR. When relay 5TR is operated by energy of 75 code frequency, the energy supplied through the decoding means DM is insufficient to 30 pick up the contacts of relay 5D so that only relay 5H becomes picked up. When contact *a* of relay 5H picks up it prepares a circuit including back contact *a* of relay 5D for supplying energy to the yellow lamp Y of signal 5S.

When the train under discussion passes out of 35 section 1T, coded energy is again supplied to relay 1TR from battery 1TB by the operation of the contact of relay 1CTP. However, it is assumed that with the train now in advance of section 1T, 40 the control relay CR will be released, and as a result, coded energy of 75 code rate will be supplied to relay 1CTP by the circuit which is traced from terminal B, over contact *a* of code transmitter 15CT, over back contact *a* of relay CR, over contact L in its closed position, and through 45 the winding of relay 1CTP to terminal C.

The relay 1TR follows the coded energy supplied thereto over the rails of section 1T, and as a result, the relay 1H picks up, but relay 1D remains released.

When contact *b* of relay 1H picks up, the supply of coded energy to relay 5CTP is changed from the 75 code rate to the 180 code rate, and when contact *d* of relay 1H picks up it interrupts 55 the stick circuit previously traced for relay 1SR and relay 1SR releases, its front contact *a* additionally interrupting the relay stick circuit.

Energy coded at the 180 code rate is now supplied to relay 5TR from battery 5TB, and as a result, relay 5H remains picked up and relay 5D becomes picked up to prepare the circuit for supplying energy to the green lamp G of signal 5S.

At this time, the winding of relay OVR is connected across the terminals of battery 5TB by the circuit including contact *c* of relay 1HR.

When the train under consideration advances a substantial distance beyond section 7T, the control relay CR will again become picked up, and will cause the coded energy supplied to relay 1CTP to be changed from the 75 code rate to the 180 code rate so that coded energy of a 180 code rate is supplied to relay 7TR from battery 7TB over the rails of section 7T. Accordingly, relay 7D becomes picked up to prepare the circuit for supplying energy to the green lamp G of signal 7S.

It will now be assumed that the system is to be restored to its deenergized condition. Accordingly, the control contact L is operated to its open position, interrupting the supply of energy to relay 1CTP, and relay 1CTP releases and remains released, thereby cutting off the supply of energy to track relay 7TR. As a result, relay 7TR releases and remains released, thereby cutting off the supply of energy through the decoding means DM to relays 7H and 7D.

When contact b of relay 7H releases, it interrupts the supply of 180 code energy from the coding device 180CT to relay 5CTP, and since contact b of relay 7SR is released at this time, energy is not supplied to relay 5CTP on release of relay 7H, and the contact of relay 5CTP releases and remains released, thereby cutting off the supply of energy to the track relay 5TR from battery 5TB over the rails of section 5T. As a result, the supply of energy to relays 5H and 5D is interrupted and these relays release.

When relay 7H releases, its contact d in the stick circuit previously traced for relay 7SR is closed, but this circuit is interrupted by front contact a of relay 7SR at this time so that relay 7H remains released. Also, contact c of relay 7H interrupts the circuit for connecting the winding of relay OVR across the terminals of battery 5TB so that when the signaling equipment is deenergized there is no load on the battery 5TB. The equipment is now restored to its original condition as originally described.

The proper operation of the approach relay 7AR and the track relay 5TR is affected by the voltage of the energy supplied from the battery 5TB to the track rails. If the voltage of the energy supplied from the track battery to the rails of section 5T is too low the track relay 5TR may fail to operate under conditions of low ballast resistance, while under conditions of high ballast resistance the relay 7AR may not operate to establish the circuit of the lamps of signal 7S until a train approaches much closer to the signal than is desired.

On the other hand if the voltage of the energy supplied from the battery 5TB is too high, the relay 7AR may operate continuously, irrespective of whether or not section 5T is occupied, particularly under conditions of low ballast resistance. If the relay 7AR should operate when section 5T is vacant it would cause the lamps of signal 7S to be lighted unnecessarily, thereby causing unnecessary consumption of energy.

In addition, if relay 7AR should operate when section 5T is vacant, the relay 7SR will be energized and will maintain the supply of energy to relay 5CTP and thus prevent deenergization of the coded track circuit for section 5T.

As explained above, when the signaling system for the track stretch is operating, the relay 7H is picked up and its contact d in the pick-up circuit for relay 7SR is closed. If conditions are such that relay 7AR operates even though section 5T is vacant the relay 7APR will be picked

up and complete the pick-up circuit for relay 7SR so that relay 7SR is picked up and closes its contact a in the relay stick circuit. Accordingly, when contact L is operated to cut off the supply of energy to section 7T for the purpose of deenergizing the coded track circuit equipment, and the relay 7H releases so that its front contact d in the circuit of relay 7SR is open, the relay 7SR will be maintained energized by current supplied over its own contact a, and the relay contacts will remain picked up with the result that energy of 75 code frequency is supplied over front contact b of relay 7SR and back contact b of relay 7H to relay 5CTP and it operates to supply energy from battery 5TB to the rails of section 5T. This energy will operate relay 7AR and cause relay 7APR to remain picked up to establish the circuit for supplying energy to the lamps of signal 7S, and to establish a circuit for supplying energy to relay 7SR.

This system is arranged to insure proper operation of the equipment at all times regardless of variations in operating conditions. As explained above, whenever the coded track circuit equipment for section 5T is required to operate the relay OVR is connected across the terminals of the battery 5TB. If the voltage of the battery 5TB is relatively low, the relay OVR will be released and its contact a will shunt the resistance R2 so that this resistance does not restrict the supply of energy from the battery 5TB through the winding of relay 7AR and the resistance R1 in multiple to the track rails and thus to relay 5TR. Accordingly, at this time, even though the voltage of the energy supplied from the battery is relatively low, the energy supplied from the battery will be of a value such as to be certain to operate the track relay 5TR and to also be certain to operate relay 7AR when an approaching train advances within the distance of the signal 7S at which it is desired to have the signal lighted. In addition, as the voltage of the battery 5TB is relatively low, the energy supplied from the battery to the rails of section 5T, even under conditions of low ballast resistance, will not cause operation of relay 7AR unless section 5T is occupied.

On the other hand, if the voltage of the battery 5TB is relatively high, the relay OVR will be picked up and its contact a will interrupt the circuit shunting the resistance R2 so that this resistance limits the energy supplied from the battery 5TB. As the voltage of the battery is relatively high, the energy supplied to the track rails 1 and 2 of section 5T, even though limited by the resistor R2, will be effective to operate the track relay 5TR even during periods in which the ballast resistance is relatively low. Furthermore, as the voltage of the battery 5TB is relatively high, the energy supplied through the relay 7AR will be effective to operate the relay when a train advances beyond the point at which it is desired to have lighting of the signal 7S initiated. In addition, even though the voltage of the battery is relatively high, the resistor R2 limits the supply of energy from the battery 5TB through the winding of relay 7AR to a value such that even under conditions of low ballast resistance the relay 7AR will not operate unless section 5T is occupied. As relay 7AR will not operate unless section 5T is occupied, it will not prevent release of relay 7SR when the signaling equipment is to be deenergized.

In addition it will be seen that the circuit of relay OVR is established as soon as the relay

7H picks up so that as soon as conditions require energy to be supplied from battery 5TB the relay OVR is connected across the terminals of the battery. Furthermore, the circuit of the relay OVR is maintained until after the relay 7SR releases so that when the equipment is being deenergized the relay OVR prevents improper operation of relay 7AR as long as relay 7SR remains picked up so that there is no possibility that relay 7SR will fail to release because of improper operation of relay 7AR.

Although I have herein shown the arrangement of apparatus embodying my invention as employed in a normally deenergized coded track circuit signaling system arranged for a single direction of train movement, it will be apparent to those skilled in the art that my invention is also applicable to other railway signaling systems, especially normally deenergized coded track circuit signalling systems arranged for two direction operation.

Although I have herein shown and described only one form of railway signaling apparatus embodying my invention, it is to be understood that various changes and modifications may be made therein within the scope of the appended claim without departing from the spirit and scope of my invention.

Having thus described my invention, what I claim is:

In a coded track circuit signaling system, in combination, a stretch of railway track divided into a plurality of track sections including a first and a second section through which traffic moves in the order named, each of said track sections having at the entrance end thereof a code following track relay operated by coded energy supplied over the section rails from the exit end of the section, means for at times supplying coded energy to the rails of said second section at the exit end thereof, a code detecting relay which is picked up in response to operation of the track relay for said second section, a signal governing movement of traffic from said first section into said second section, said signal including a lamp, a track battery the voltage of which varies a substantial amount during the life of the bat-

tery, a code following approach relay, a transmitting relay effective when rendered active to recurrently connect said battery and the winding of said approach relay in series across the rails of said first section at the end thereof adjacent said second section, said approach relay being proportioned so that during normal battery voltage conditions the approach relay does not respond to energy of the value supplied from said battery through the relay winding to the track rails when said first section is unoccupied and is rendered operative only on the increase in current supplied through the relay winding under predetermined conditions of occupancy of said first section, a slow release approach repeater relay energized in response to operation of said approach relay, a directional stick relay having a pick-up circuit including front contacts of said approach repeater and code detecting relays and having a stick circuit including its own front contact and a back contact of said code detecting relay, means for rendering said transmitting relay active when said code detecting relay is picked up and also when said code detecting relay is released provided said directional stick relay is picked up, an overvoltage relay connected across the terminals of said track battery when said directional stick relay or said code detecting relay is picked up, said overvoltage relay having a contact which is picked up when and only when the voltage of said battery exceeds a predetermined value, and means effective only when said overvoltage relay is picked up for including a resistance in the circuit through which energy is supplied from said track battery through the approach relay to the rails of said first section.
